(57) **CLAIM**

The design of a cover for goggle straps, as shown and described.

DESCRIPTION

FIG. 1 is a perspective view of a cover for goggle straps in an open position;

FIG. 2 is a perspective view from below of a cover for goggle straps in an open position;

FIG. 3 is a front view of a cover for goggle straps in an open position;

FIG. 4 is a rear view of a cover for goggle straps in an open position;

FIG. 5 is a left side view of a cover for goggle straps in an open position;

FIG. 6 is a right side view of a cover for goggle straps in an open position;

FIG. 7 is a plan view of a cover for goggle straps in an open position;

FIG. 8 is an inverted plan view of a cover for goggle straps in an open position;

FIG. 9 is a perspective view of a cover for goggle straps in a closed position;

FIG. 10 is a top plan view of a cover for goggle straps in a closed position;

FIG. 11 is a front view of a cover for goggle straps in a closed position;

FIG. 12 is a rear view of a cover for goggle straps in a closed position;

FIG. 13 is a left side view of a cover for goggle straps in a closed position;

FIG. 14 is a right side view of a cover for goggle straps in a closed position; and,

FIG. 15 is a perspective view in situ of a cover for goggle straps.

The inverted, i.e., bottom plan view of the cover for goggle straps in a closed position is the mirror image of the plan view shown in FIG. 10. The cover can be any material, such as fabric.

1 Claim, 6 Drawing Sheets
